UNITED STATES PATENT OFFICE.

MANEL G. TORMO, OF NEW YORK, N. Y., ASSIGNOR TO OLIVE DEIMEL, OF NEW YORK, N. Y.

CLOSURE FOR CONTAINERS.

Application filed December 19, 1924. Serial No. 756,888.

To all whom it may concern:

Be it known that I, MANEL G. TORMO, a citizen of the United States, and a resident of New York city, in the county and State 5 of New York, have invented certain new and useful Improvements in Closures for Containers, of which the following is a specification.

This invention relates to stoppers for 10 containers of various kinds and is particularly designed for collapsible tubes of thin sheet metal.

The object of the invention is to provide 15 a closure of this character in which the cap can be applied by direct pressure downwardly, without turning or screwing, and will be retained by the resiliency of the side walls of the cap; and which cap is provided with a resilient liner or plug that will 20 be compressed at the opening in the container end and securely close the container; and which cap can be readily removed and replaced when desired on the container.

The accompanying drawing showing one 25 embodiment of my invention, Figure 1 shows the cap about to be applied to the container.

Fig. 2 shows the cap secured on the container.

Fig. 3 is a plan view partly in section.

Fig. 4 shows the cap in elevation, broken away at the bead.

Fig. 5 shows the tube top portion.

Fig. 6 shows the liner plug.

Fig. 7 is a cross section through the tube 30 top and cap, above the bead partly applied and flexed.

The device as shown comprises a cap 2 of the usual cylindrical form having an end 35 wall 3 closing the top and, preferably a bead at the top, forming a groove 5 on the inner wall. This cap that is made of resilient metal, is provided with a bead 6 at the lower end, as by rolling the edge of the cap, which bead extends inwardly.

The container 7 as shown is of the collapsible tube form with a rigid metal disk 8 at the top. This disk has a set of ribs 9 extending outwardly from its outer side, 40 of which four are shown. At the bottom of each rib 9 is a groove 10 extending laterally. The disk 8 has a small bore 11 at the upper end, that is formed somewhat conical as shown at 12. It is to be understood that 45 the closure can be applied to any form of a

container having its top constructed substantially like the disk 8, of metal, glass or other material.

The cap 2 has its bore of a diameter equal to that at the outer side of the ribs 9 above the groove so that it can fit thereon. The cap is applied to the disk 8 and will engage the ribs 9, and being resilient will spring outwardly at these four points, readily permitted by the spring of the cap, that will 60 obviously tend to flatten between such points. The cap is then pushed down on the disk 8 until the grooves 10 are reached by the bead 6 on the cap, whereupon the cap will spring inwardly to its former or 65 normal shape, and the bead will enter the grooves 10 which will permit the cap above the head to engage the outer side of the ribs above the grooves, as indicated in Fig. 1. This will cause the cap to be securely 70 retained on the disk, but it can be withdrawn by pulling it outwardly, assisted possibly by compressing the cap inwardly at opposite sides between the ribs.

For the purpose of securely sealing the 75 contents of the tube against escape into the cap, I provide a sealing liner or plug 13 of suitable material, such as soft rubber. This is somewhat crescent-shaped with a lower extension 14. The upper and outer margin 80 of the plug is of a size to enter the groove 5 at the top of the cap, that will retain the plug as a liner in the cap, but its concave upper face will normally extend away from the top 3 of the cap a considerable distance. A slight depression or bore 15 may be 85 formed in the upper wall of the cap at the center. The plug is so shaped that when the closure is applied the lower extension 14 will seat on the conical disc top 12. As 90 the cap is pushed down the liner will be forced toward the top 3 of the cap. This will tend to flatten the convex portion of the liner, that will be assisted by the depression 15, and when the cap is pushed down to 95 engage the bead with the grooves, the part 14 of the liner will be very tightly pressed against the conical end 12, and securely seal the opening into the tube.

A device of the character is very simple 100 in construction, comprising merely a cap of sheet metal, the liner plug of rubber, in connection with the disk 8 provided with the ribs and grooves, and also the neck as set forth.

What I claim is:

1. In combination, a container having the neck provided with a series of upright ribs on the outer side, each rib having a lateral groove at the base, a cap of resilient metal provided with a bead at the lower edge projecting inwardly, the bore of the cap having a diameter adapted to snugly fit the said neck at the rib portions, whereby the cap can be applied to said neck and be expanded by said ribs until the bead will reach the grooved portions of the ribs, whereupon return of the cap to normal shape will cause the bead to enter said grooves and lock the cap on the neck.
2. In combination, a container having the neck provided with a series of upright ribs on the outer side, each rib having a lateral groove at the base, a cap of resilient metal provided with a bead at the lower edge projecting inwardly, the bore of the cap having a diameter adapted to snugly fit the said neck at the rib portions, whereby the cap can be applied to said neck and be expanded by said ribs until the bead will reach the grooved portion of the ribs, whereupon return of the cap to normal shape will cause the bead to enter said grooves and lock the cap on the neck, a liner plug of crescent shape placed inside of the cap engaging the upper portions of the cap, which plug is compressed against the said neck on application of the cap.
3. In combination, a container having the neck provided with a series of ribs on the outer cylindrical side, and a reduced bore at the neck extending downwardly from the upper edge, each rib having a lateral groove at the base, and a closure cap of resilient metal provided with an annular groove in its inner wall at the top and a bead on the lower edge that projects inwardly, the bore of the cap having a diameter adapted to snugly fit said neck at opposite rib por-
- tions, whereby the cap can be applied to said neck and be expanded by said ribs until the bead will reach the grooved portions of the ribs, whereupon return of the cap to normal shape will cause the bead to enter said rib grooves and lock the cap on the neck, a resilient liner plug of substantially crescent shape placed inside of the cap with its outer margin engaging the said groove portions of the cap, said neck being conical at the top, said resilient plug having its lower face compressed against said top on application of the cap.
4. In combination, a container having the neck provided with a series of ribs on the outer cylindrical side, and a reduced bore at the neck extending downwardly from the upper edge, each rib having a lateral groove at the base, and a closure cap of resilient metal provided with an annular groove in its inner wall at the top and a bead on the lower edge that projects inwardly, the bore of the cap having a diameter adapted to snugly fit said neck at opposite portions, whereby the cap can be applied to said neck and be expanded by said ribs until the bead will reach the grooved portions of the ribs, whereupon return of the cap to normal shape will cause the bead to enter said rib grooves and lock the cap on the neck, a resilient liner plug of substantially crescent shape placed inside of the cap with its outer margin engaging the said groove portions of the cap, said neck being conical at the top, said resilient plug having its lower face compressed against said top on application of the cap.

Signed at New York city, on December 17th, 1924.

MANEL G. TORMO.
